UNITED STATES PATENT OFFICE.

DONALD D. BURCH, OF OKMULGEE, OKLAHOMA.

APPARATUS FOR CEMENTING OIL WELLS.

Application filed June 21, 1927. Serial No. 200,424.

This invention relates to apparatus for cementing oil wells and more particularly to an improvement of the oil well cementing apparatus disclosed in my prior patent, No. 5 1,603,447, granted October 19, 1926, for casing shoes.

An important object of the invention is to so rearrange the structure disclosed in this prior patent that the plug is much more readily drilled out after the cementing operation 10 has been completed and is much more readily installed for service.

A further object of the invention is to produce a device of this character so constructed 15 that the elements thereof may be formed and separately shaped and the assembly thereof completed by the purchaser, thus materially reducing the cost of shipment and the difficulties of transportation. In this connection, it 20 is pointed out that oil wells are often located at almost inaccessible points and the transportation of heavy materials is always a serious problem.

These and other objects I attain by the construction shown in the accompanying drawings, wherein for the purpose of illustration is shown a preferred embodiment of my invention and wherein:—

Figure 1 is a vertical sectional view through 30 apparatus for cementing wells constructed in accordance with my invention, a plug being disclosed as seated upon the upper end of the control element to close the upper ends of the conduits thereof;

Figure 2 is a horizontal sectional view therethrough.

In accordance with the present invention, I provide a casing shoe 10, the interior wall 40 of which is circumferentially recessed, as at 11, to provide shoulders or seats preventing movement of a cast concrete plug 12, which may be formed therein. In combination with this casing shoe, I provide a control element, which comprises a central casing 13 having 45 in communication with the upper end thereof of a conduit or conduits 14, the ends of which are downwardly directed and extend below the lower level of the casing. Communicating with the bottom of the casing are conduits 50 15, the ends of which are upwardly directed and extend above the top of the casing. Inferiorly, the casing is provided with a valve seat 16 having cooperating therewith a check ball or check valve of any suitable character, 55 designated at 17 and seating downwardly.

In the use of the apparatus, as described,

the control element is placed in the casing shoe in alignment with the recess 11 and cement poured thereabout to form the plug 12 in which the control element is completely 60 embedded, with the exception of the fact that the ends of the conduits 14 and 15 open through the bottom and top thereof respectively.

In cementing a well, this device is attached 65 to the lower end of the casing and when the casing is at the proper position, pump pressure is applied to drive the cement through the control element where, in its passage, it lifts the check ball 17, passes the same and 70 discharges from the lower end of the casing shoe through the conduits 14. After the cement has been completely forced through the control element which may be determined by the fact that a plug 18 following the same 75 seats upon the upper end of the control element and closes the upper ends of the conduits 15, the pump pressure is relieved and any tendency of the cement to return to the interior of the casing through the control element will be prevented, by reason of the fact that the check 17 will seat and will be held seated by the pressure of the incoming cement.

When the cement has fully set, the plug 18 85 which, if desired, may be of cement and the plug 12 are drilled from the shoe in the usual manner. The control element may be formed from tin or galvanized iron of light gauge and will not materially interfere with the drilling 90 operation, as is the case with a heavy metallic body, such as described in my prior patent above mentioned. While I have above referred to the plug 12 as being constructed of concrete, it will readily be understood that 95 this plug may be constructed of any castable material which is readily drilled from the shoe without damage to the drill. Among such substances might be mentioned in addition to the concrete previously mentioned 100 wood or paper pulp and plaster of Paris. All of such substances, however, should be material which can be readily pulverized.

Since the construction hereinbefore set forth is capable of a certain range of change 105 and modification without materially departing from the spirit of the invention, I do not limit myself to such specific structure except as hereinafter claimed.

I claim:—

1. In combination, a casing shoe having its interior wall recessed, a cast concrete plug

110

within the shoe and having portions extending into said recess whereby the plug is held against movement with relation to the shoe, a control element cast within the plug having means permitting fluids to flow through the plug from the upper to the lower end thereof, but preventing return flow of such fluids, the control element comprising a casing, a conduit communicating with the upper 10 end of the casing and extending downwardly through the bottom of the plug, a second conduit communicating with the bottom of the casing and extending upwardly through the top of the plug and a downwardly seating check valve controlling communication between opposite ends of the casing.

2. In combination, a casing shoe, a cast concrete plug within the shoe and secured against movement therein with relation to the shoe, said plug having a central chamber therein with a valve seat at the lower

end thereof, a plurality of conduits arranged eccentrically to the chamber and extending between said valve seat and the upper end of the plug forming communications between the interior of said chamber and the interior of the casing shoe above the plug, other conduits arranged eccentrically to the chamber intermediate the other conduits and extending between the lower end of the plug and the upper end of the chamber forming communication therebetween, a ball valve in the chamber adapted to cooperate with the valve seat, said ball valve permitting fluids to flow from the upper end of the plug through the chamber and through the lower end thereof but being seated by the return flow of fluid from the bottom of the plug to prevent the fluid from passing through the plug.

In testimony whereof I hereunto affix my signature.

DONALD D. BURCH.
